UNITED STATES PATENT OFFICE.

CLARENCE H. KELSEA, OF BELMONT, MASSACHUSETTS, ASSIGNOR TO PETER GRAY & SONS INC., OF CAMBRIDGE, MASSACHUSETTS, A CORPORATION OF MASSACHUSETTS.

FOCUSING DEVICE FOR LANTERNS.

Application filed December 3, 1921. Serial No. 519,632.

To all whom it may concern:

Be it known that I, CLARENCE H. KELSEA, a citizen of the United States, residing in Belmont, in the county of Middlesex and State of Massachusetts, have invented an Improvement in Focusing Devices for Lanterns, of which the following description, in connection with the accompanying drawings, is a specification, like characters on the drawings representing like parts.

This invention relates to an illuminating apparatus of that character in which a source of light is adjustable with relation to a reflector, and is herein shown as embodied in a lantern provided with an incandescent lamp and especially adapted among other uses to be employed as a signal lantern on railways, vessels and the like.

The invention has for its object to provide a simple, efficient and inexpensive device for adjusting the electric lamp or other source of light with relation to the reflector to obtain the desired beam of light projected by the reflector.

The invention also has for its object to provide an adjusting device, with which single or double contact sockets for the electric lamp may be used as desired, and which enables the electric circuit for the lamp to be independent of the metal casing of the lantern, thereby avoiding the inclusion in the lamp circuit of the metal casing and the resistance offered thereby, together with the consequent heating of the casing with its attendant objectionable features.

To this end, the adjusting device is provided with a sliding member which supports the socket for the incandescent lamp, and with a rotatable member which supports the sliding member and upon which the latter slides to effect radial adjustment of the lamp with relation to the axis of the reflector.

The rotatable member is preferably made in two parts and of insulating material and cooperates with a supporting member, which may and preferably will be a part of the metal housing for the reflector.

These and other features of the invention will be pointed out in the claims at the end of this specification.

Fig. 1 is a longitudinal vertical section of a signal lantern embodying this invention.

Fig. 2, an enlarged detail of the adjusting device shown in Fig. 1 with the parts in a position substantially at right angles to that shown in Fig. 1.

Fig. 3, an end elevation looking toward the left in Fig. 2.

Fig. 4, a section on the line 4—4, Fig. 2, looking toward the right.

Figs. 5 and 6, views like Fig. 3 with the sliding member in extreme adjusted positions on opposite sides of the center position shown in Fig. 3, and

Fig. 7, a detail in elevation showing the engagement of the sliding member with the rotatable member.

Referring to the drawing, *a* represents the metal casing of a signal lantern of known construction and provided at its front end with the usual cover glass *b*, and at its rear end with the sliding door or cover plate *c*.

The casing *a* contains within it the reflector *d* and the metal housing *e* therefor, which is suitably supported by the casing *a* and is provided with a rear wall or back plate *f*. The reflector *d* is secured to its housing *e* by the metal clips 10, and has cooperating with it an incandescent lamp 12 whose plug member 13 is extended through an opening 14 in the rear end of the reflector and into a socket member 15, which may be of the double contact type, but which is preferably of the single contact type, as herein represented.

The socket member 15 is provided with external screw threads 16 which engage an internally threaded metal bushing 17, through which the socket member 15 is extended.

The metal bushing 17 and the socket member 15 are supported by one member of an adjusting device, which member is represented as a metal disk 20 having a central hole through which the front reduced portion of the bushing 17 projects and against which a shoulder 22 on the bushing bears and is soldered thereto. The metal disk 20 is mounted to slide radially on a rotatable member of the adjusting device, and said rotatable member is herein shown as composed of two circular disks 24, 25 of insulating material, which are secured together and mounted on the back plate *f* of the reflector housing to rotate as one piece.

In the present instance the disk 24 is provided with a hub 26 which is extended through a circular hole in the back plate *f*, and whose center is concentric with the horizontal axis of the reflector *d*; and the disk 25 is provided with an annular flange 27, which extends over the hub 26 and engages the plate *f* on the side opposite to the disk 24. The disks 24, 25 may be secured in fixed relation to the plate *f* by bolts 30 located substantially diametrically opposite and extended through the sliding disk 20, the disks 25, 24, and a metal disk 31 on the outside of the disk 24. The bolts 30 are extended through elongated slots 32 in the metal disk 20, and, when loosened, permit said metal disk to be moved linearly from its central position shown in Fig. 3 to the extreme positions on opposite sides of the center shown in Figs. 5 and 6.

The metal disk 20 is guided in its radial movement from the extreme position shown in Fig. 5 to its extreme position shown in Fig. 6 by bent fingers 34 on the disk 20 which project into a guideway or diametrical slot 35 in the outer surface of the disk 25.

Provision is made for permitting the bushing 17 and the lamp socket 15 to be moved with the sliding disk 20, and to this end the disks 24, 25 are provided with elongated slots 36, see Figs. 1 and 4, which coincide and practically form one slot through which the bushing 17 extends.

The slots 36 extend in the same direction as the slots 32 in the slideable disk 20. The bolts 30 have mounted upon them between the disk 20 and the heads of the bolts, spring washers 38, which serve to keep the disks 24, 25 connected together so as to be rotated as one piece, after the bolts 30 have been loosened sufficiently to permit the said disks to be turned or rotated in the opening in the plate *f*. The socket member 15 has mounted on it one connector 40 for the electric circuit in which the lamp 12 is included, and said socket member also carries a plug 41 of insulating material, through which is extended a contact member 42, which has attached to it a second connector 43 for said electric circuit. The connector 40 is fitted on to the socket member 15 between the bushing 17 and the nut 23 thereon.

From the above description it will be seen that by means of the rotatable adjustable member and the sliding adjustable member, the lamp 12 may be adjusted radially into any desired position with relation to the horizontal axis of the reflector, and by turning the socket member 15 in its bushing 17, the lamp 12 may be adjusted longitudinally with relation to a vertical plane through the focal axis of the reflector, and that these adjustments may be made in a minimum time.

Furthermore, it will be observed that the members of the adjusting device are accessi-

ble to the operator by removing the cover plate *c*.

It will also be observed that the electric circuit of the lamp 12 is from one connector as 43 through the plug member 42, filament of the lamp 12, socket member 15 and connector 40, and does not include the housing *f*, *e*, for the reflector *d* or the casing *a*, and as a result, resistance due to said casing and housing, with corresponding consumption of current is avoided, and heating of said parts is also avoided, which enables the lantern to be handled without objection on the part of the operator, and therefore enables the lamp to be adjusted while in use without inconvenience to the operator.

It will also be observed, that the desired adjustment may be effected in a minimum time.

So also the parts of the adjusting device are simple and inexpensive, and when the lamp has been adjusted, it may be firmly secured, whereby the lamp socket is to all intents and purposes secured against movement, thereby avoiding accidental derangement of the lamp adjustment.

One embodiment of the invention is herein shown, but it is not desired to limit the invention to the particular construction shown.

Claims:

1. In an illuminating apparatus, in combination, a reflector, an incandescent lamp, a threaded socket member for said lamp, a bushing on said socket member, and an adjusting device for said lamp, comprising a sliding member supporting said bushing, a rotatable member on which said sliding member slides, means for supporting said rotatable member, and means for securing said rotatable member in fixed relation to its supporting means and said sliding member in fixed relation to said rotatable member.

2. In an illuminating apparatus, in combination, a reflector, an incandescent lamp, a socket member for said lamp, and an adjusting device for said lamp, comprising a rotatable member having an elongated slot into which said socket member is extended, and a supporting member for said socket member mounted on said rotatable member to slide thereon in the direction of the length of the slot therein and to rotate therewith.

3. In an illuminating apparatus, in combination, an incandescent lamp, a socket member for said lamp, and an adjusting device for said socket member comprising a rotatable member provided with an elongated slot extended laterally with relation to the axis of said rotatable member and through which said socket member is extended and in which it is movable in the direction of the length of said slot, and a supporting member for said socket member

connected with said rotatable member to slide thereon lengthwise of said slot and to rotate with said rotatable member.

4. In an illuminating apparatus, in combination, a light source and an adjusting device for said light source comprising a disk of insulating material rotatable about the axis of said light source and provided with an elongated radially extended slot, a metal disk supporting said light source and

mounted on said insulating disk to slide thereon radially with relation to the axis of said disk and in the direction of the length of said slot, and means for securing said metal disk in its adjusted position on said insulating disk. 15

In testimony whereof, I have signed my name to this specification.

CLARENCE H. KELSEA.
